(57) **CLAIM**

The ornamental design for a “picture frame moulding,” as shown and described.

DESCRIPTION

FIG. 1 is a perspective view of picture frame moulding showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top view thereof; and,

FIG. 7 is a bottom view thereof.

The picture frame moulding is shown broken away at the center in FIGS. 1 and 4-7 to indicate indeterminate length.
